UNITED STATES PATENT OFFICE.

ROBERT H. DOWNING, OF ST. LOUIS PARK, MINNESOTA.

DENTURE GRINDER.

Application filed March 13, 1926. Serial No. 94,521.

This invention relates generally to means for operating dental articulators, and is particularly directed to a device adapted to be non-positively connected with, and provides 5 means whereby differential motions may be communicated to an articulator, whereby the movable part of the articulator can be translated horizontally forwardly and backwardly, laterally vertically, and given substantially 10 rotary motion.

An object is to provide a power operable device, certain elements of which can be lengthened or shortened to abuttingly engage with the movable member of the articulator 15 in certain desired relations to obtain the motions above mentioned.

In a device of this kind, it is desirable that the articulator be quickly attached or detached, and disposed and adjusted in relation 20 to its operating device, and it is further desirable that certain length adjustments of the operating members be had to obtain substantially universal differential movements of the movable member of the articulator, 25 according to the work in hand.

The features of the invention relate to the general mode of operation of the device, as well as to the detail structure of the various parts per se, and in combination.

30 An important feature of the invention relates to a translatable adjustable cam engaging device carried by a translatable articulator engaging member, the adjustable device having anti-friction members thereon adjustable for alternate engagement with one or the other of cams carried by a rotating member, adapting the articulator engaging member to be given motions of a character desired for the work in hand.

40 In the accompanying drawings forming part of the specification—

Figure 1 is a plan section showing the device set for obtaining substantial simultaneous movement of the articulator operating elements in the same direction;

Figure 2 is a side elevation corresponding to Figure 1, the clamping member being shown in section;

50 Figure 3 is a plan section corresponding to Figure 1 showing the high points of the inner and outer cams engaged with the translatable member.

Figure 4 is a plan section showing the

translatable members positioned for obtaining simultaneous movements in opposite 55 directions; and

Figure 5 is a cross section on line 5—5 of Figure 1.

This device has a hollow base 1, having attached to and extending vertically upward 60 from its top three pedestals or standards respectively, 5, 6 and 7. Each standard has at its top a horizontal cross member respectively indicated at 8, 9 and 10, and each cross member is bored to form a horizontal bearing, with the axes of all bores parallel, extending longitudinally of the base and lying substantially in the same horizontal plane. Rotatably journaled in the cross member 8 is a shaft 11 at the outer end of 70 which is non-rotatably secured a pulley-like element 12, providing a peripheral belt groove 13. This rotatable element 12 has formed integrally therewith, on one of its faces, two circular cams mutually concentric, 75 and concentric with the axis of rotation of the element 12. The cams are configurated for action in a direction parallel to the rotative axis of the element 12 and therefore 80 parallel with the axes of the bearing bores of the cross members 9, 10. In this instance, see Figure 3, the high and low points of the cams are aligned on a common diameter, and the low point 15 of the outer cam lies adjacent the high point 17 of the inner cam, while 85 at the opposite side of the rotative axis of the element 12, or at the opposite side of the journal 11, the high point 16 of the outer cam lies adjacent to the low point 18 of the inner cam. Thus, when certain translatable members described below, are operatively engaged with the outer cam said members are substantially reciprocated in the opposite 90 directions, and when one of the members is engaged with the inner cam, said members are substantially simultaneously reciprocated 95 in the same direction.

In each of the cross members 9 and 10 is mounted a translatable element 20 and each element 20 preferably has an extension member adjustably attached thereto. The element 20 is slidably but non-rotatably held in its bearing, and for this purpose each member 20 is provided with a diametrically related cross pin 21 engageable in a corresponding horizontally disposed diametric

slot 22 at the outer end of the cross member. The connection for preventing rotation of the member 20 may be made in any preferred manner, however. The forward end of each member 20 is bored and threaded as at 23 for cooperation with the reduced threaded end 24 of the extension member 26.

A jam nut 25 secures the outer member after rotatable adjustment. One of the members 20 has an anti-friction roller 28 rotatable on a horizontally disposed stub shaft 29, and the periphery of this roller is engageable with or by the outer cam. The element 20 of the other translatable member 15 has horizontally slidably disposed at its outer end a diametrically related shaft 35, at each opposite end of which is rotatably secured an anti-friction roller, outer and inner respectively 36, 37. All rollers preferably have cushioned peripheries, the cushioning being provided in this instance by bands of rubber fitting within peripheral grooves of the rollers.

The distance between the adjustably disposed rollers is greater than the distance between adjacent portions of inner and outer cams, so that when the shaft 35 is slid in its bearing in a direction diametrically of the cams or pulley, the outer anti-friction element can be engaged with the outer cam, or the inner anti-friction element can be engaged with the inner cam, to obtain differentiated movements of the element 20.

The arrangement is such that only one 35 anti-friction device is engaged at a time.

One of the slideable elements thus has adjustable means thereon engageable with and by either cam whereby the elements can be caused to simultaneously reciprocate, 40 respectively in the same, or opposite directions.

The outer ends of the length-adjustable translatable elements, abuttingly engage with the spring-retractable, movable element of the dental articulator described below, which is clampingly held upon the base 1 by a specially designed clamp. By adjusting the lengths of the translatable elements virtually any desired movement can be communicated 45 to the movable part of the articulator, so that the grinding operation can be carried out in exactly the manner desired.

In Figures 3 and 4 positions of the movable portion of the articulator are shown in 55 dotted lines, and as shown in Figure 3, simultaneous movements of both sides of this part, by the translatable elements, are obtained in same direction as the movements of the translatable elements, which are in this 60 instance respectively operated by inner and outer cams. In Figure 4, the device is shown set for obtaining substantially simultaneous movement of the elements in opposite directions, thus obtaining a substantially rotary 65 motion of the movable part of the grinder.

The present device is designed to actuate an articulator substantially of the design shown, and although the articulator per se forms only an auxiliary part of the apparatus, some idea of its structure and operation is needed. 70

The articulator (see Figs. 1 and 2) comprises a fixed part 40 having a forward extension 41 to which a lower holder 42 is attached, and upon the upper side of which holder is mounted a lower set of teeth 43, to be ground. Extending vertically upwardly from the fixed part 40 are two pins 46 alined in a direction at right angles to direction of reciprocation of the translatable elements 20. A movable part 45 overlies the part 40 and pins 46, and has lateral forward extensions 47 as guide pieces, each guide piece having two curved surfaces 48, 49 arranged at an angle to one another.

A spring 50 is attached as at 51 to the fixed part and has its upper end overlying and frictionally and compressingly engaging the part 45 (see Fig. 1).

The movable part 45 also has a holder 55 connected thereto, carrying an upper set of teeth 56. The arrangement of upper and lower parts of the articulator is such that the teeth supported by respective holders, are arranged for proper occlusion or "bite".

When the movable part 45 is translated horizontally by means of the impinging elements 20 against the action of the spring 50, proper grinding motion between the sets of teeth 43, 56 is obtained, and the surfaces of the guides cause substantially simultaneous movements of the part 45 horizontally forwardly, backwardly, laterally and vertically. Thus when the elements 20 move together upward, forward and backward motions of the movable part are obtained, and when the elements 20 move in opposite direction lateral 105 rotative motions of the movable part are obtained, according to the length adjustments of the translatable elements 20.

It will be noted that no positive connection between the ends of the elements 26 and guides 47 is necessary, inasmuch as a spring 50 operates to return the movable part after translation rearwardly. Therefore, the articulator can be quickly attached and detached. 110 In other words, the translatable elements only abut or impinge the movable part of the grinder.

In order to positively obtain proper occlusion between the sets of teeth to be ground, and in order to permit the movable section of the articulator to come to rest during a portion of the grinding cycle, the cams are so configurated that no engagement with or by the anti-friction rollers is 120 possible for a short period. This arrangement is shown in Figures 1, 2, and 4. With this disposition of the peripheries of the anti-friction elements in relation to the cams, action upon the elements will, of 125 130

course, not be continuous but inasmuch as the cams are herein virtually inclined to planes, the lost motion will be slight.

The clamping device, which is also a feature of the invention, comprises a hollow clamping member or boxing 60 open at its clamping side, and adapted for engagement at that side with an extension of the lower or stationary part 40 of the articulator, as shown in Figure 2. The device is adapted for ready placement or removal. The top is centrally slotted as at 61 to permit the clamp to be translatable engaged with or disengaged from a screw threaded post 62 and projecting upwardly from the base 1. The base is provided near that edge remote from the pulley with upstanding lugs 63, with which the outer lower side of the clamp is abuttingly engaged. A wing nut 65 secures the device in operative position, and when it is desired to remove the clamp, the wing nut 65 is loosened, and that side of the clamp engaged with the lugs is raised to clear the same. The clamp, as before stated, is then moved in a direction longitudinally of the base from engagement with the extension of the fixed part 40 of the articulator, the slot 61 allowing this withdrawal.

30 I claim as my invention:

1. A device of the class described comprising a pulley having cams thereon configurated for action in direction parallel with the axis of rotation of the pulley, and a translatable element operable by the cam having adjustable cam engaging rollers thereon movable in unison for alternate engagement with a respective cam.

2. In a device of the class described a pulley having cams thereon configurated for action in direction parallel with the axis of rotation of the pulley, elements translatable mounted adjacent the pulley, one of said elements having thereon a shaft adjustable diametrically thereof, said shaft having a cam engaging roller at each end, and said shaft translatable for alternately engaging a roller with a respective cam.

3. In a device of the class described, a rotatable member having cams thereon, configurated for action in the same direction, and translatable members having their ends engagable by one of the cams for reciprocation thereby, one of said elements having adjustable cam engaging means thereon alternately engageable with either cam.

4. In a device of the class described, a rotatable member having cams of unlike configuration and members translatable mounted, having ends engageable by the cams for simultaneous reciprocation thereby, said translatable members having extensions adjustably connected therewith.

5. In a device of the class described, a rotatable element having cams thereon, trans-

latable elements having ends engageable by one of the cams, and shiftable means upon one of the elements for alternate engagement with or by the other cam.

6. In combination with a dental articulator having a movable part, a rotatable element having cams thereon configurated for action in a direction toward the articulator, translatable elements engageable with and by one cam for reciprocation thereby, and having their ends abuttingly engaged with the movable part of said articulator, one of said translatable elements having adjustable cam engaging means thereon adapted to be alternately engaged with either cam.

7. In combination with a dental articulator having a movable part, a rotatable element having cams thereon, translatable elements engageable with and by one cam for reciprocation thereby, and having the ends abuttingly engaged with the movable part of said articulator, one of the elements having adjustable cam engaging means thereon adapted for alternately operatingly conditioning said element for operation by either cam.

8. In combination with a dental articulator having a movable member, a rotatable element having two adjacently disposed cams configurated for action in the same direction translatable mounted elements having their ends abuttingly engageable with the cam and having their opposite ends abuttingly engageable with the movable member of the articulator respectively at opposite sides, one of said translatable elements having adjustable means thereon alternately engageable with the cams.

9. In combination with a dental articulator having a movable member, a rotatable element having two circular concentric cams, concentric with the axis of the rotation of the element, said cams configurated for action in a direction parallel to the axis of rotation of the element, translatable mounted elements having their ends engageable with or by the cams and having their opposite ends abuttingly engaged with the movable element of the articulator, one of said translatable elements having means thereon adjustable for alternately obtaining movement of said element by either cam.

10. In combination with a denture grinder, having a spring retracted increasingly movable element, translatable elements abuttingly engaged with the movable element of the grinder, and a rotatable element having cams thereon engageable with the translatable elements for substantially simultaneous moving the same toward and away from the grinder, and means upon one of the elements shiftable for alternate engagements with one of the cams for obtaining substantial simultaneous movement of the elements

in opposite direction whereby the movable grinder element in one instance is given a reciprocative motion and in the other a rotative movement.

11. In a device of the class described, a rotatable element having two circular cams concentric with its axis of rotation and configurated for cam action in direction parallel with said axis of rotation, two elements 10 slidably mounted, each having one end engageable with one of the cams for reciprocation thereby, and one of the elements having adjustable means thereon for alternately connecting it with either cam to reverse its direction of reciprocation relative to its companion element.
12. A device of the class described, a base having means thereon for clamping a denture grinder, a pair of standards oppositely 20 related to said clamping means, each having an element translatablely mounted thereon, said elements being parallel and extending in direction toward said clamping means and

space above said base, a grooved pulley rotatably mounted intermediate of said elements with its axis of rotation parallel with direction of reciprocation of the elements, 25 said pulley having cams thereon mutually concentric and concentric with the axis of rotation of the pulley, adapted to engage or to be engaged by said reciprocable elements, and adjustable means upon one of the reciprocable elements alternately engageable with one of the cams, whereby by adjustment of said means, simultaneous reciprocatory movements of the elements in the same and in opposite direction can be obtained.

13. A device of the class described comprising cams movable in unison, and a member translatable by the cams, and having cam engaging elements adjustable in unison for alternately engaging the cams to cause translation of the member.

In witness whereof, I have hereunto set my hand this 11th day of March, 1926.

ROBERT H. DOWNING.
